UNITED STATES PATENT OFFICE.

THOMAS M. JAMISON, OF MEMPHIS, TENNESSEE.

DESIGN FOR A LAMP-FIXTURE.

SPECIFICATION forming part of Design No. 34,822, dated July 23, 1901.

Application filed May 23, 1901. Serial No. 61,629. Term of patent 3½ years.

To all whom it may concern:

Be it known that I, THOMAS M. JAMISON, a citizen of the United States, residing at Memphis, in the county of Shelby and State of Tennessee, have invented and produced a new and original Design for Lamp-Fixtures; and I do hereby declare the following to be a full, clear, and exact description of the invention, such as will enable others skilled in the art to which it appertains to make and use the same.

This invention relates to a design for a lamp-fixture; and, as shown in the accompanying facsimile-drawing, it consists of a fount surmounted by a suspending device, a stem pendent from the fount, a frame of approximately oval shape arranged with its major axis at a right angle to the stem and having its upper bar straight and attached centrally to the said stem and having its lower bar cut away, posts pendent from the ends adjacent the gap or opening, and a lower frame of approximately square form having rounded corners and attached at its upper end to the lower ends of the posts.

The stem 2 has a suspending-eye at its upper end and a fount 1 adjacent said end, the sides of the fount being parallel, its bottom rounding, and the upper portion tapering and

having beads and coves. An oblong frame 3 of approximately oval form, with its top bar 30 straight and the middle portion of its lower bar omitted, is attached centrally of its top bar by a coupling to the lower end of the stem and is arranged with its major axis at a right angle thereto. A valve appears at one end 35 of the frame. Parallel posts 4 are pendent from the ends of the lower bar adjacent the gap or opening therein and have rounded terminals. A frame 5 of approximately square form and having rounded corners is pendent 40 from the posts 4. The part 6 is opposite the gap or opening in the lower bar of the frame 3 and in line with a valve between the two frames. The stem 2 and frames 3 and 5 present a twisted effect. 45

Having thus described the invention, what is claimed as new is—

The design for a lamp-fixture, substantially as herein shown and described.

In testimony whereof I affix my signature 50 in presence of two witnesses.

THOMAS M. JAMISON. [L. S.]
